UNITED STATES PATENT OFFICE.

JOE N. FENDER, OF DALLAS, TEXAS.

WELL CABLE-PUMP.

1,347,806.

Specification of Letters Patent. Patented July 27, 1920.

Application filed October 24, 1919. Serial No. 332,994.

To all whom it may concern:

Be it known that I, JOE N. FENDER, a citizen of the United States, residing at Dallas, in the county of Dallas and State of Texas, have invented a new and useful Well Cable-Pump, of which the following is a specification.

This invention relates to an improved pump and more particularly to one adapted 10 to be used in connection with deep wells for pumping oil or other fluids and the object thereof is to provide an improved construction whereby it will obviate the necessity of employing a long line of extra pipe and the 15 usual pump rod which gives so much trouble.

A further object of the invention is to provide an improved pump employing a cable in lieu of the ordinary pump rod, and which includes a novel construction of 20 pump device facilitating the pumping operation, and also the removal of the parts for cleaning or repair or any other cause.

With the above and other objects in view which will appear as the description 25 proceeds, the invention resides in the combination and arrangement of parts and in the details of construction hereinafter described and claimed, it being understood that within the scope of what is claimed, changes in 30 the precise embodiment of the invention shown, can be made without departing from the spirit of the invention.

In the accompanying drawings:

Figure 1 is a vertical sectional view of 35 the upper portion of the pump;

Fig. 1^A is a similar view of the lower portion of the pump;

Fig. 2 is a sectional view taken on the line 2-2 of Fig. 1^A.

Referring to the drawings in which like 40 reference characters designate similar parts throughout the several views, the numeral 10 designates a well casing which is driven into the ground at a suitable depth so as 45 to strike a subterranean stream or supply of fluid, such as oil, water or the like. The casing is shown extended to the cap rock 11, of the stream 12, from which the fluid supply is drawn. Mounted in the bottom of 50 the casing is a perforated strainer or suction pipe 13 which is connected at its upper end to the lower end of the cylinder or working barrel 14 by a pipe coupling 15, preferably internally threaded to engage the corresponding 55 external threads of the adjacent ends of the pump cylinder and suction pipe.

The pump cylinder or working barrel extends upwardly at a suitable distance, and has the upper end thereof provided with a reduced perforated swage nipple 16, the 60 perforations below said nipple or swaged portion being indicated at 17 in the tapering or conical upper end of the pump cylinder or working barrel, so as to receive the short section or pump rod 18 therethrough. Said 65 pump rod is made in a series of sections the lower end of which is connected by a coupling 19 with a suitable valved pump plunger 20 having the usual passage 21 therethrough, and the cage 23 mounted on 70 the upper end thereof to retain the ball valve 24 in position, said ball being designed to open on the downward stroke of the plunger and to close on the upward stroke of the plunger so as to lift the fluid 75 within the pump cylinder or working barrel. The connection of the pump rod is made with a reduced extension 25 extending from the upper end of the cage, the coupling preferably being internally threaded for 80 engagement with the corresponding external threads of the pump rod and the extension 25 as clearly shown in Fig. 1^A of the drawing.

Mounted in the lower end of the pump 85 cylinder or working barrel above the perforated suction pipe 13, is a valve member 26 the same having a cage 27 on the upper end thereof which retains a ball valve 24, except that the ball valve 28 is open on the 90 upward stroke of the plunger 20 and closed on the downward stroke thereof in opposite relation to the operation of the ball valve 24, thus providing one of the valves to support or maintain the column of liquid with 95 in the pump cylinder or working barrel and the casing, at all times.

Above the coupling 19, is disposed a similar coupling 29 which is limited in its upward movement by the nipple 16 and which 100 also permits separation of the parts for the purpose of cleaning or repair and also facilitates assemblage thereof. The pump cylinder or working barrel carries externally below the nipple 16, a supporting collar or seat 105 30 having an enlarged upper end portion provided with a suitable leather packing collar or washer 31 seated therein, and forming a water or fluid tight connection with the lower end of a pipe section 32 which fits over 110 the working barrel at the upper end thereof and is provided at its upper end, with a

swaged nipple 33 beneath which said pipe is tapered and provided with suitable apertures 34 for the escape of the fluid therethrough. There is provided between the 5 nipple 16 and the nipple 33, a coupling 35 similar to the couplings 19 and 29, the coupling 35 being limited in its upward movement by the nipple 33, although the short sectional pump rod or shaft 18, comprising 10 three sections as shown, extends through the nipple 33 and considerably above the same for connection with a cable 36 which is employed in lieu of the usual pump rod, thereby permitting the cable to be wound upon a suitable drum for raising the 15 parts, while permitting reciprocation of the plunger in the usual or any preferred manner. The connection of the pump rod with the cable is made through the medium of a coupling 37 and suitable clamps 38 anchoring the extremity of the cable above the coupling, which latter is preferably provided with a threaded socket in its lower end to which the upper end of the pump rod 20 is connected as shown at 39, said ends being externally threaded for this purpose.

The lower end of this pipe or outer working barrel or pump cylinder 32 rests upon the collar 30 in engagement with the packing washer 31, immediately above which the pipe 32 is provided with a series of apertures 40. Above and below the apertures or openings 40 in the wall of the pipe 32, there are disposed collars or lock nuts 41 between 30 which are clamped an annular leather or rubber packing sleeve 42 which fits against the interior wall of the well casing.

In the operation of the device, it should be noted that there is slight space between 40 the pump cylinder or working barrel 14 and the outer pump cylinder or working barrel mounted above and over the same and formed by the pipes 32, so that as the plunger is reciprocated, the fluid such as oil, when the device is used in connection with 45 an oil well, will be caused to pass successively by the valves 28 and 24 and above the plunger, being prevented from passing downwardly by said valves when in closed 50 positions, but being effectively strained in passing through the perforated suction pipe 13. This prevents entrance of foreign matter to the pump and as the fluid is lifted, it will pass out through the openings 17 from 55 the pump cylinder or working barrel into the outer or upper pump cylinder or working barrel 32 or pipe forming the same, and then pass through the openings 34 to be lifted in the well casing to be discharged. 60 However, a certain amount of fluid after passing through the openings 17 will pass between said cylinders 14 and 32, and enter the space between the same through the 65 openings 40 behind the packing sleeve 42 and being forced outwardly under the pres-

sure, caused by the fluid or oil, will seal it against the casing and make a perfect fluid tight joint which will prevent the fluid from passing therebetween. As the pump is continued to be operated the fluid will be discharged from the top of the casing and should it be desired to pull the pump for any cause, it will be simply necessary to wind on the cable which will cause the coupling 35 to strike the nipple or sleeve 33, thus lifting the pipe or outer pump cylinder 32 from its seat upon the washer 31 of the collar 30, thus relieving the pressure and allowing the fluid to be discharged downwardly into the casing around the collar 30 and further permitting the coupling 29 to engage the nipple or sleeve 16 and to raise the working valve and parts associated therewith, as soon as the head of oil above the valve is relieved, the plunger moving 85 upwardly with the rod during this operation, and thereby permitting the pump to be drawn out.

Having thus fully described my invention, what I claim is:

1. A pump rod comprising a casing, a working barrel in said casing and providing an annular space between the same, a strainer coupled to the lower end of the barrel, a ball valve in the lower portion of the barrel, a plunger operating in the barrel having a passage therethrough, a cage on the plunger, a ball valve retained therein and co-acting with the seat formed at the upper end of the plunger, a sectional pump rod, 95 couplings connecting the sections of the rods and connecting the lower end of the rod with said cage, a cable detachably connected to the upper end of the rod, said barrel having a reduced upper end portion and apertures adjacent thereto, a seat on the barrel, an upper barrel sitting over said first named barrel and providing a space therebetween, said upper barrel being provided with a reduced upper end and apertures therebeneath, said 100 reduced portions of the barrels being designed for engagement by couplings connecting sections of the rod whereby to successively lift the upper and lower barrel, and a packing in the upper barrel and the casing 110 adjacent said seat, said upper barrel being provided with openings at said packing.

2. The combination with a working barrel having a valved lower end and a nipple at its upper end with apertures therebeneath; of a valve and plunger operating in said barrel, a rod connected to said plunger, operating means connected to said rod, a collar connecting sections of the barrel and having a seat on its upper end, there being a space between said collar and the usual well casing, a pipe around said barrel and resting on said seat at its lower end, said pipe having a nipple at its upper end and apertures therebeneath, enlargements on the rod be- 130

neath said nipples, the nipple of the barrel being at a greater distance from the enlargements beneath it than the nipple of the pipe is above the enlargement beneath it, said pipe having openings in said lower end communicating with a space between pipe and valve, and a sleeve forming a packing anchored to the pipe above and below the apertures therethrough to seal against the casing.

10 3. In a pump, the combination with a sectional barrel including an inner section, a plunger operating therein, means for actuating said plunger, an upper barrel section, said upper section being located outwardly 15 of the lower valve section and provided with a space between the upper portion of the lower section and the lower portion of the upper section, means to permit the escape of fluid at the upper ends of said barrel sections, 20 said upper section having apertures through its wall near the lower end thereof, a collar connecting to said lower section and having a seat on its upper end for the lower end of the upper section, a flexible packing 25 surrounding said upper section and spaced therefrom providing an annular chamber around said apertures, the upper and lower ends of the packing sleeve being provided with inturned flanges and means for anchoring 30 said flanges to said upper section to prevent the escape of fluid therebetween.

4. In a pump, the combination with a sectional barrel including an inner section, a plunger operating therein, means for actuating said plunger, an upper barrel section, 35 said upper section being located outwardly of the lower barrel section provided with a

space between the upper portion of the lower section and the lower portion of the upper section, means to permit the escape of fluid 40 at the upper end of said barrel sections, said upper section having apertures through its wall near the lower end thereof, a collar connecting to said lower section and having a seat on its upper end for the lower end of 45 the upper section, a flexible packing surrounding said upper section and spaced therefrom providing an annular chamber around said apertures, the upper and lower ends of the packing sleeve being provided 50 with inturned flanges, means for anchoring said flanges to said upper section to prevent the escape of fluid therebetween, said barrel sections being provided with perforated swaged nipples at their upper ends and tapered 55 portions immediately therebeneath having apertures therethrough, said barrels being adapted to be disposed in spaced relation to the well casing and said packing being designed to contact with the interior of 60 said casing, and means on said rods for successively displacing the upper and lower sections of the barrel when lifting the rods out of the casing, whereby to unseat said upper section from said collar and relieve the fluid 65 pressure thereabove, whereby said plunger and valve can be removed.

In testimony that I claim the foregoing as my own, I have hereto affixed my signature in the presence of two witnesses.

JOE N. FENDER.
